WEFT STOP MOTION

Victor Marie Joseph Ancet, Lyons, France, assignor to Regina S. A., Tangiers, Morocco

Application March 18, 1948, Serial No. 15,557
In France April 18, 1947

6 Claims. (Cl. 139—370)

1

This invention relates to weft stop motions for use in circular looms of the type, in which the weft yarn is laid in the shed by the shuttle at a distance from the fell of the fabric and is subsequently beaten up by a member, which travels with the shuttle to the rear thereof and may, in some looms, be the following shuttle. More particularly, the invention is concerned with a novel stop motion for use in a circular loom of the kind referred to, which is adapted to engage the weft yarn between the point where it leaves its shuttle and the point where it is beaten up, and operates, when the weft yarn is missing or broken, to stop the loom.

The stop motion of the invention is of the electrical type and includes a circuit containing a pair of contacts, of which one is fixed and the other movable. The contacts are carried by a support traveling with the shuttle to the rear thereof and the support also carries a freely rotatable wheel having radial teeth adapted to engage the weft yarn lying between warp threads and not yet beaten up. The engagement of the ends of the teeth with the weft yarn determines the relative positions of the teeth and the warp threads and, if the yarn is broken or missing, the relative positions change and this results in the operation of means for moving the movable contact relatively to the fixed contact. Such movement of the movable contact then alters the circuit, as, for example, by closing it, and this causes the operation of conventional means for stopping the loom.

In the preferred form of the new stop motion, the freely rotatable wheel, when in engagement with the weft yarn, forces the warp threads, between which the yarn lies, slightly out of their normal positions. A detector mounted to travel with the wheel and connected to the movable contact normally lies out of engagement with the warp threads, but, if the weft yarn breaks or is absent, the warp threads enter the spaces between the teeth and engage the end of the detector, so that, as the detector advances with the wheel, it is swung and moves the movable contact to alter the circuit and stop the loom.

In a modified construction, the toothed wheel is not supported in fixed position on a support traveling with the shuttle but on one end of a lever pivoted on the support and carrying the movable contact on its other end. The lever is acted on by a spring and urges the wheel toward the sheet of warp threads, within which the weft yarn lies. The ends of the teeth of the wheel engage the weft yarn and this limits the movement

of the lever and wheel. However, if the yarn is missing, the lever is swung to cause the teeth of the wheel to pass between the warp threads and, in such movement of the lever, the movable contact is moved relatively to the fixed contact, the circuit is altered, and the loom is stopped.

For a better understanding of the invention, reference may be made to the accompanying drawings, in which:

Fig. 1 is a diagrammatic view in side elevation showing one form of the new stop motion and associated parts;

Fig. 2 is a view in side elevation of part of the stop motion;

Figs. 3 and 4 are diagrammatic plan views showing the manner in which the stop motion operates;

Fig. 5 is a horizontal sectional view showing the interior of a part of the stop motion; and

Figs. 6 and 7 are diagrammatic plan views showing a modified form of the new stop motion.

In the circular loom, of which portions are illustrated in Fig. 1, the shuttle 10 is of the cylindrical type and it is carried by a frame 11 provided with a roller 12, which rolls over the loom reed. The shuttle contains a package of weft thread 13, which issues from an opening in the top of the shuttle and passes through a guide eye 14a in an upward and rearward extension 14 from frame 11, forming a trolley. The shuttle travels through the warp shed, which opens ahead of the shuttle and closes behind it, and the weft thread issuing from the guide eye 14a lies close to the fell of the fabric and is beaten up by a beat-up wheel 15, which is mounted on a pin 16 on an arm 17 advancing with the shuttle. The beat-up wheel may be of the construction disclosed in my copending application, Serial No. 610,437, filed August 13, 1945.

The weft stop motion of the invention comprises a toothed wheel 18 having long narrow teeth 18a and rotatably mounted on a spindle 19 carried by a rod 20, which extends through a bearing 21 and is adjustable lengthwise of the bearing by means of a screw 22 threaded through the bearing and engaging an arm 23 fast on the rod. The bearing is mounted on a rod 24, which extends through an opening in one end of an arm 25 mounted to rotate about the central axis 26 of the loom at the same rate as the shuttle. The lower end of rod 24 is threaded and carries a nut 27, which can be turned to adjust the vertical position of the rod. The rod 24 is encircled by a spring 28, one end of which engages bearing 21 and the other end of which bears against the end

of arm 25. When the wheel 18 is in its proper position of adjustment, one or more of its teeth 18a engage the length of weft thread 13 between the guide eye 14a in trolley 14 and the beat-up wheel 15 and at a point close to the beat-up wheel. As a result the warp threads 29 are slightly deformed, so that they lie outwardly from their normal positions 29a.

A plate 30 of insulating material is mounted fast on spindle 19 above the wheel 18 and a shaft 31 is mounted for oscillation in openings through plate 30 and through a metal plate 32 attached to the upper face of plate 30 and grounded through a connection 33. At its lower end, the shaft 31 carries a detecting finger 34 having a toothed end, which lies outwardly beyond the edge of plate 30 and terminates inwardly from the ends of the teeth 18a on wheel 18. At its other end, the shaft carries a contact 35, which is connected by a spring 36 to a pin 37 on the plate 30. The spring tends to hold contact 35 against a stop pin 38 on plate 32 and, in this position of the parts, the finger 34 extends radially. A contact spring 39 is carried by a stud 40 mounted in an opening in plate 30, and the stud is provided with an arm 41 projecting outwardly beyond the edge of plate 30 and provided at its end with a terminal post 42. Post 42 is connected in a circuit including a battery 43 and a solenoid 44, which, when energized, opens a switch 45 in a circuit 46 controlling the supply of current to the motor 47 driving the loom.

In the normal operation of the loom, as shown in Fig. 3, the arm 25 rotates about the axis of the loom with wheel 18 rolling along the horizontal length of weft thread 13 between the guide eye 14a and the beat-up wheel 15. The engagement of the ends of the teeth with the weft thread forces the warp threads 29 outwardly from the axis of the loom, so that the toothed end of finger 34 does not engage the threads. If the weft thread breaks, as shown at 13a, the warp threads 29 move back to their normal positions 29a and enter between the teeth 18a on wheel 18. The toothed end of finger 34 then comes in contact with either the warp threads or the fabric 48, and, as arm 25 continues its movement, the finger 34 is swung to the position shown in Fig. 4. At the same time, the contact 35 on shaft 31 engages the contact spring 39 closing the circuit through solenoid 44, so that the solenoid is energized and opens switch 45. This results in cutting off the supply of current to the motor 47 and the loom stops.

The modified construction shown in Figs. 6 and 7 includes a wheel 49 having long narrow teeth 49a and generally similar in construction to wheel 18. Wheel 49 is mounted for rotation on one end of a lever 50 pivoted on an arm 51, which rotates about the loom axis. Lever 50 is grounded through a connection 52 and carries a contact 53, which, upon swinging of the lever, engages a contact 54 on an arm 55 mounted on and insulated from arm 51. One end of lever 50 is connected through a spring 56 to an arm 57 fast on arm 51, the spring urging the lever to swing to cause contacts 53, 54 to engage. Contact 54 and its arm 55 are in a circuit 58 through a solenoid 59, which controls a switch 60 and includes a battery 61. Switch 60 is in a circuit controlling the loom driving motor (not shown) and, when opened, cuts off the supply of current to the motor.

In the normal operation of the apparatus shown in Figs. 6 and 7, the toothed wheel 49 rolls over

the horizontal length of weft thread 62 between the beat-up wheel (not shown) and the guide eye of trolley 63 of the frame carrying the shuttle. The engagement of the ends of the teeth 49a with the weft thread causes the wheel and lever 50 to be held against the action of spring 56, so that contacts 53, 54 are open. If the weft thread breaks, as indicated at 62a (Fig. 7), the wheel 49 is free to be moved outwardly by the action of spring 56 on lever 50, with the teeth 49a of the wheel penetrating the sheet of warp threads. This movement of the wheel and lever causes contact 53, 54 to be closed so that solenoid 59 is energized, switch 60 is opened, and the supply of current to the motor driving the loom is cut off.

What I claim is:

1. In a weft stop motion for use in a circular loom having a shuttle traveling through the warp shed to lay a weft yarn between the warp threads and parallel to and spaced from the fell of the fabric and a device traveling with and behind the shuttle to beat up said yarn, the combination of a support traveling with the shuttle and means mounted on the support for altering a circuit, said means including a pair of contacts, one contact being movable and inserted in the circuit, a freely rotatable wheel having radial teeth engageable with the weft yarn to determine the relative positions of the teeth and the warp threads between which the yarn lies, and means operable, when the weft yarn is absent, by a change in the relative positions of the teeth and warp threads to move the movable contact relatively to the other contact.

2. In a weft stop motion for use in a circular loom having a shuttle traveling through the warp shed to lay a weft yarn between the warp threads and parallel to and spaced from the fell of the fabric and a device traveling with and behind the shuttle to beat up said yarn, the combination of a support traveling with the shuttle, a freely rotatable wheel on the support having radial teeth engageable with the weft yarn to hold the warp threads, between which the yarn lies, out of their normal positions, the warp threads entering the spaces between the teeth, when the yarn is absent, a pair of contacts carried by the support, one contact being movable, and means connected to the movable contact and engaged and moved by the warp threads, when they lie between the teeth, to move said contact.

3. In a weft stop motion for use in a circular loom having a shuttle traveling through the warp shed to lay a weft yarn between the warp threads and parallel to and spaced from the fell of the fabric and a device traveling with and behind the shuttle to beat up said yarn, the combination of a support traveling with the shuttle, a freely rotatable wheel on the support having radial teeth engageable with the weft yarn to hold the warp threads, between which the yarn lies, out of their normal positions, the warp threads entering the spaces between the teeth, when the yarn is absent, a pair of contacts carried by the support, one contact being movable, and a finger carried by the support and connected to the movable contact, the finger being engaged by the warp threads, when they enter between the teeth, and swung to move the movable contact relatively to the other contact.

4. In a weft stop motion for use in a circular loom having a shuttle traveling through the warp shed to lay a weft yarn between the warp threads and parallel to and spaced from the fell of the fabric and a device traveling with and behind

the shuttle to beat up said yarn, the combination of a support traveling with the shuttle, a freely rotatable wheel on the support having radial teeth engageable with the weft yarn to hold the warp threads, between which the yarn lies, out of their normal positions, the warp threads entering the spaces between the teeth, when the yarn is absent, a pair of contacts carried by the support, one contact being movable, and a finger carried by the support and connected to the movable contact, said finger normally extending radially of the wheel and having an end engaged by the warp threads, when they enter between the teeth, the movement of the support thereafter causing the finger to swing and move the movable contact relatively to the other contact.

5. In a weft stop motion for use in a circular loom having a shuttle traveling through the warp shed to lay a weft yarn between the warp threads and parallel to and spaced from the fell of the fabric and a device traveling with and behind the shuttle to beat up said yarn, the combination of a support traveling with the shuttle, a spindle carried by the support and extending in the same general direction as the warp threads, a wheel freely rotatable on the spindle and having teeth engageable with the weft yarn to hold the warp threads, between which the yarn lies, out of their normal positions, the warp threads entering the spaces between the teeth when the

yarn is absent, a plate fast on the spindle, a fixed contact carried by the plate, a finger pivoted on the plate and having an end engaged by the warp threads, when they enter between the teeth, a movable contact attached to the finger, and a spring urging the finger to one position, the movement of the support after the end of the finger has been engaged by the warp threads causing the finger to swing and move the movable contact relatively to the other contact.

6. In a weft stop motion for use in a circular loom having a shuttle traveling through the warp shed to lay a weft yarn between the warp threads and parallel to and spaced from the fell of the fabric and a device traveling with and behind the shuttle to beat up said yarn, the combination of a support traveling with the shuttle, a fixed contact on the support, a lever pivoted on the support, a movable contact on one end of the lever, a freely rotatable wheel on the other end of the lever, the wheel having radial teeth engageable with the filling yarn and holding the wheel and lever in one position, and a spring urging the lever toward a second position and effecting, when the weft yarn is absent, the movement of the lever to alter the relative positions of the contacts.
